MACHINE TOOL SLIDEWAY AND METHOD
OF MAKING THE SAME

William Wallace Potter, Pawtucket, R. I.

Application June 29, 1932, Serial No. 620,023

4 Claims. (Cl. 82—32)

My invention refers particularly to slideways for machine tools, and to illustrate or exemplify it, I will use the case of its embodiment in the turret slide of a turret lathe. I do not limit myself, however, to this particular application of it, since my invention consists in whatever is described by or is within the terms or scope of the appended claims.

Where it is desirable to have one body slide upon another with maximum rigidity and accuracy of alignment, for example as in the case of machine tools, it has been the custom to provide two surfaces, scraped or ground to the requisite degree of accuracy, and these surfaces have usually been of cast iron. To add to the length of their life, these bearing surfaces have been made of hardened steel. There is a hardened steel strip on the base and a contacting steel strip on the slide. With this construction, it is difficult to 10 grind the contacting surfaces to a proper degree of accuracy, as the bearing surface is longitudinal of the grain, or fibers, of these steel strips, and holding down straps must be scraped into position after the original bearing has been machined.

By my invention, I provide a construction free 25 of these objections and one that results in a simple and effective bearing and one by which original alinement may be easily secured. The bearing surface on one element or member, at least, will be across the ends of the fibers of the steel. This gives long life and enables the holding down straps to be first set up without any laborious and costly alining operation.

In the drawing:—

Fig. 1 is a side elevation partially in section of 35 a turret slide embodying my invention;

Fig. 2 is an end elevation partially in section.

The turret lathe base, 10, and the turret slide, 11, are or may be of usual, or conventional construction, and need no special description. Upon the top of base, 10, at opposite sides are fastened horizontal hardened steel strips, 12, which are ground flat and true with each other. Secured to the slide, above each strip, are a series of 40 hardened steel plugs, 13, whose bottom faces constitute the sole bearing contact between slide and base. These plugs are inserted in cored holes 14, in the slide; are adjusted each by a screw 15, as hereinafter explained; and are then firmly fixed 45 in position by pouring a molten metal, expandable upon cooling (such as type metal), into the hole 14, through port, 16. The hardened plugs, 13, are ground perfectly flat upon faces, 17, to form the bearing. The slide is held down on the base, 10, by straps, 18 and 19, bolted to the slide by cap screws 20, and these straps respectively overlap lips 21 and 22, on base, 10.

I first attach the hardened steel strips to the base 10 grinding them on the surface after they 50 are fastened to the base so they are perfectly

flat and true with each other. At the same setting that I grind these surfaces, I also machine the lips 21 and 22, on the base 10, so that they are perfectly parallel with the surfaces of strips 11. I then place the turret slide with the plugs 13, inserted in the holes 14, securely bolting the straps 18 and 19 to the slide. Then by means of elevating screws 23, that bear at one end against the top of base, 10, I raise the slide 11, until straps 18 and 19, bear with the proper pressure on the 10 lips 21 and 22, of the base. I next set up screws 15, until surfaces 17, of plugs 13 bear evenly on the surface of strips 11 and then pour the molten expandable metal into the holes 14, through port 16. This metal, upon cooling, forms a filling 24, 15 that firmly secures plugs 13 in their adjusted position. Finally screws 23 are removed from the slide.

What I claim is:—

1. A bearing having contacting slides at least 20 one of which has its bearing surface across the grain of the metal the contacting surfaces of such slides being extended in the direction of sliding movement, one of such surfaces being continuous and the other being composed of portions that 25 are spaced apart in the direction of sliding movement.

2. A method of constructing machine tool slideways which includes the acts of truing parallel slide surfaces on the machine base, adjustably 30 mounting on a member to be slidably supported on the base, elements with faces that slidably contact with said surfaces, adjusting such elements relative to such surfaces to assure the desired pressure of the sliding surfaces upon one 35 another and then fixing such elements in their adjusted positions.

3. A bearing having sliding surfaces which include a strip of metal with a flat and true bearing face, and a member movably mounted thereon 40 which has a plurality of spaced plugs with ends exposed for contact with the bearing surface of said strip and means for permanently fixing said plugs in a previously adjusted position with their 45 ends in contact with the strip.

4. A bearing for machine members, one being a flat surface support for the other which is slidable thereon, said bearing comprising opposing slide surfaces and means for holding at least one 50 of such slide surfaces in a permanently fixed position relative to the other, comprising a cavity opening towards the other slide surface from which projects a part having the opposing slide surface with the latter exposed on the outside of said cavity, the cavity being larger than the 55 part therein and a metal filler in the cavity in holding contact with surfaces of said part in the cavity and with the cavity walls.
